UNITED STATES PATENT OFFICE.

WILLIAM LUXMORE, OF CHICAGO, ILLINOIS.

SPRING TERMINAL CLIP.

1,273,250.

Specification of Letters Patent. Patented July 23, 1918.

Application filed January 27, 1916. Serial No. 74,570.

To all whom it may concern:

Be it known that I, WILLIAM LUXMORE, a citizen of the United States, residing at Chicago, in the county of Cook and State of Illinois, have invented a certain new and useful Improvement in Spring Terminal Clips, of which the following is a full, clear, concise, and exact description, reference being had to the accompanying drawings, forming a part of this specification.

My invention relates to spring terminal clips and to that class of conductor terminal fasteners which is conveniently made of a strip of brass or other metallic ribbon and formed so that two portions of the strip oppose each other in order to grip the conductor.

In one of the devices of the art a tongue was stamped from a portion of a metallic strip and formed to fit into a slot adapted to lie directly above the tongue when in normal position. In this device when it was desired to attach a conductor the spring was pressed down far enough to admit the conductor between the tongue and spring and released. The edges of the tongue and slot in this prior construction pass one another so that when a wire is placed in position in the clip it is either subjected to a shearing action by the edges of the tongue and spring in their tendency to pass each other, or if the tongue and slot edges do not so closely engage to effect a shearing action, the conductor, when small is often drawn into a loop, thus preventing firm engagement and good electrical contact.

It is the object of this invention to provide a spring clip that will be as cheaply manufactured as those of the past, but free from their shortcomings. With the use of my invention various sized conductors may be inserted into the clip and will be firmly held in good electrical contact therewith in a manner which positively prevents cutting, shearing or looping the conductor no matter how small or fragile it may be.

In accomplishing this, I contemplate the provision of abutting members carried by and formed of the body and spring portions which members receive the shearing stresses incident to the structure and withhold them from the conductor.

More specifically, in the construction of my device I arrange the parts so that the engaging portions abut one another. In

those of my devices in which cutting edges exist they are made to overlap so that a conductor clamped between the body and spring portions rests against positive stops.

It will be seen, therefore, that the force exerted by the spring will be taken up by the whole or a large part of the conductor, engaging the opposing portions.

My invention will be more readily understood by reference to the accompanying drawings in which,

Figure 1 is a plan view of the strip of metal used in constructing the device shown in Fig. 2 after the punching process and before it is bent into the form of the finished product.

Fig. 2 is a perspective view of this embodiment of my invention.

Fig. 3 is a cross-sectional view of the device shown in Fig. 2.

Fig. 4 is a perspective view of a modification of my invention.

Fig. 5 is a perspective view of another modification of my invention.

Fig. 6 is a sectional view of the device shown in Fig. 5.

Fig. 7 is a perspective view of another modification of my invention; and

Fig. 8 is a sectional view of a clip wherein the parts are formed to make knife edge contact with a conductor.

Similar characters of reference refer to similar parts throughout the drawings.

Referring to Fig. 1 in which I have illustrated a strip of spring metal 9 to be used for the clip: For this purpose I prefer brass, first for its elastic properties, and second for its cheapness. Punched from the strip 9 are two slots 10-11 separated by a web 12. At the same time a tongue 13 is punched and folded on the dotted line (Fig. 1) and is of suitable length and width slightly less than that of the slot 11.

After one portion of the strip is bent to form the spring member 15 the tongue extending first upwardly and then downwardly through the slots 10-11 on either side of the web 12 is formed so that a flat portion 16 engages the web 12 of the spring. When the finger piece 15^a is pressed down an opening is provided between the web and the portion 16 for the accommodation of a conductor. The conductor is held, by the tension of the spring on which it lies, in contact with the flat portion 16 of the tongue 110

and inasmuch as there are no cutting edges to pass each other no shearing or bending of the conductor occurs.

I prefer to make the tongue 13 substantially V shaped in order that the opening provided for the conductor will enlarge as the spring is depressed.

In assembling the device, the tongue 13 with the hook already shaped, may be brought into a perpendicular position whereupon the spring portion is depressed in such a manner as to cause the tongue to be extended through the slot 10. Upon the insertion of the tongue and the depression of the spring, the tongue is bent at the base so that upon the release of the spring the free end of the tongue will extend downwardly through the slot 11, and the flat portion 16 of the tongue will engage the web 12 to limit the movement of the spring member. If it is desired, the hook may be formed after the end of the tongue is inserted in the slot 10.

In the modification shown in Fig. 4 the spring 20 has provided therein a slot 20^a into which extends the tongue 18 provided with ears 19—19 extending at right angles to the tongue and adapted to engage the spring 20 on the flattened portion 22. In this modification after the punching and folding process the assembling consists in forcing the portions on either side of the slot 20^a apart sufficiently to admit the ears 19—19 carried by the tongue 18. The portions are then forced toward each other sufficiently to permit the ears to overlap and engage the flat portion 22. It is clear that the force exerted by the spring 20 will be taken up by the projecting ears 19 of the tongue 18, and a conductor held by the clip will be engaged by the ears 19 of the tongue 18 and spring 20.

The device of Fig. 5 is shown attached to the carbon of a dry cell and comprises a body portion 23 and the spring 25. From the body portion 23 is stamped a slot 28 so as to provide ears 29—29 extending toward each other. It will be seen that the arm 31 is inserted through the slot 28 and the spring holds the arm 31 in engagement with the ears 29—29 thereby limiting the movement of the spring. Upon depression of the arm 31 an opening is provided for the reception of a conductor. Upon releasing the arm the conductor is firmly held by the tension of the spring in engagement with the ears 29—29. As illustrated in Fig. 7 this modification consists in a base 33 formed into a V at 34. Slots 35 are provided in the V and separated by a flat web 37 of the member 34. The arm 39 is inserted through the slots 35 and the tension of the spring holds the upper surface of the arm in engagement with the lower surface of the web 37. An opening is provided for the con-

ductor upon depression of the arm 39. When the arm is released the conductor is secured between two flat surfaces and cannot be cut or bent.

In Fig. 8 I have illustrated a clip in section. It consists in a base 40, a spring 41, and a tongue 43. As shown the tongue 43 is dished at 45 so that its edges engage the conductor in a manner which increases the grip upon the conductor. The assembling operation in this modification is the same as in the assembling of the device of Fig. 2.

Thus it will be seen that in each of my devices the conductor is secured between the body portion and the spring member and the parts are so arranged that the edges of parts cannot pass each other to effect a cutting operation.

Having thus described my invention, what I claim is:

85

1. A spring terminal for electrical conductors consisting in a body portion, a spring portion, slots provided in said spring portion and separated by a web, a tongue adapted to extend through the slots and coöperate with said web, said tongue being adapted to hold a conductor between it and the web.

2. A spring terminal for electrical conductors comprising a spring member, a body member, slots provided in said spring member and separated by a web, a resistant member, substantially V shaped, formed of the body member and adapted to extend into one of said slots over said web and through the other of said slots.

3. A metallic ribbon spring terminal for electrical conductors comprising a spring member, a body member, a resistant member, one of said members provided with slots, the resilient member adapted to engage an abutment disposed between said slots.

4. A spring terminal for electrical conductors consisting in a body portion, a spring portion, one of said portions being provided with slots separated by a web, and the other portion being arranged to extend through the slots and engage one surface of the web.

5. A fastening device for electrical conductors comprising a piece of resilient metal looped on itself to form a spring and having one end forming a wire engaging portion, and a free ended resistant portion located at the opposite end of the loop and projecting through an opening in the wire engaging portion and having a face engaging an opposing face of said wire engaging portion whereby when the spring is forced toward the resistant portion a conductor may be inserted between the resistant and engaging portions and may be firmly gripped in defined position between said opposing faces by the retractive force of said spring.

6. A fastening device for electrical conductors comprising a body member and a spring member, one of said members being slotted centrally to form a projecting hooked tongue, the opposite member being provided with a slot and a retaining face, said tongue extending through the slot and normally engaging said retaining face to prevent the hook and opposite member from passing each other, whereby a small conductor may be clamped between said members without danger of shearing it.
7. A fastening device for electrical conductors formed from a single piece of flat resilient metallic ribbon having substantially greater width than thickness and comprising a flat body member, adapted to lie upon a base and be fastened thereto, an opposing spring member situated opposite said body member, one of said members being provided with a resistant member bent intermediate its length to form an angular wire engaging portion, the apex of which projects through the opposite member, said members being so formed that opposing faces of each normally abut one another whereby a conductor may be clamped between the opposing faces without shearing the conductor.
8. A fastening device for electrical conductors comprising two conductor clamping parts, one extending through the other, spring means tending to withdraw the parts away from each other to clamp between them an electrical conductor, means provided on one of the clamping parts overlapping the other clamping part for preventing the withdrawal of one part through the other, one of said clamping parts being bent intermediate its length to form an angular wire engaging portion the apex of which is located at the point of overlapping of said parts, whereby a small conductor may be clamped between said parts without danger of shearing it.
9. A binding post comprising a resilient strip flexed upon itself to provide a body member and a clamping member, one of said members being provided with an aperture and the other of said members having a portion extending through said aperture and in overlapping relation with a portion of said first-named member, and means on one of said members for guiding wires of various diameters to a position between said overlapping portions.
10. The combination with a clamping member having an aperture therethrough, of a second clamping member extending through said aperture and in overlapping relation with said first named clamping member, resilient means for urging said clamping members toward each other, and means carried by one of said members for guiding wires of various sizes to a position between said clamping members.

In witness whereof, I hereunto subscribe my name this 22 day of January A. D. 1916.

WILLIAM LUXMORE.
